(57) **CLAIM**

The ornamental design for a spiral pet treat, as shown and described.

DESCRIPTION

FIG. 1 is a front, top and left perspective view of a spiral pet treat according to our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The evenly-spaced broken lines shown in FIGS. 1 and 4-7 illustrate portions of the spiral pet treat that form no part of the claimed design. The dash-dot-dash lines shown in FIGS. 1 and 4-7 illustrate the boundary of the claimed design which forms no part thereof. The break lines shown in the middle portion of the spiral pet treat in FIGS. 1 and 4-7 indicate that the appearance of any portion of the article between the break lines forms no part of the claimed design.
